Attns.

UNITED STATES PATENT OFFICE.

HARRY LYON, OF HOLBROOK, MASSACHUSETTS, ASSIGNOR TO PERLEY E. BARBOUR,
OF QUINCY, MASSACHUSETTS.

WELTING.

Application filed August 20, 1925. Serial No. 51,375.

This invention relates to welting more particularly intended for use in connection with the manufacture of stitch-down shoes, and is of the general type disclosed and claimed in 5 my Patent No. 1,656,564, granted January 17, 1928 for welt and method of making the same, the welt of that patent, however, being designed for application to welt shoes, in that it presents a bead formation lying in the 10 shoe crease and between the inseam and out-seam of the shoe.

For a more complete understanding of this invention, reference may be had to the accompanying drawings in which

15 Figure 1 shows in perspective a piece of strip material from which the welt is made.

Figure 2 is a similar view showing the manner of cutting the strip preparatory to forming the bead.

20 Figure 3 shows the cut portion raised preparatory to rolling the core strip into position.

Figure 4 shows the core strip rolled within the surfacing layer and secured to form the 25 finished welt.

Figure 5 is a fragmentary cross section through the edge portion of a stitch-down shoe showing the welt in position.

Figures 6 and 7 are views similar to 30 Figures 2 and 4, respectively, but showing modified constructions.

Figure 8 is a top plan of a piece of completed welting showing ornamentation thereon.

35 Referring to these drawings, a substantially rectangular strip of suitable material, such as leather, as at 1, is cut inwardly from its lower face, this being the flesh side in case leather is employed, this cut being positioned

40 at 2 and extending perpendicularly to the top and bottom faces of the strip and extending to a point adjacent to the upper surface.

From the inner end of this cut 2 a cut 3 is made away from the adjacent edge 4 of the 45 strip and substantially parallel to its upper face 5, thus forming a core strip portion 6 of substantially square cross section having its walls formed by an upper grain face 5 and a lower flesh face 7 of the base strip, when of leather, substantially perpendicular to the end face 4 and integral with a thin layer 8.

The core strip and layer are bent away from the remainder of the strip, as illustrated in Figure 4, and the core is then rolled inwardly 50

between the layer 8 and the remainder of the 55 base strip so as to partially wrap the core strip, and particularly its flesh side, within the layer. These parts are fixed in position against the upper face 10 formed by the cut 3 with the edge 4 forming a flat base resting thereon, the inner margin of the upper face 5, i. e. the grain face of the core strip, being then flush with or disposed in substantial continuation of the inner edge 11 formed on the base strip by the cut 2. The welt then appears as shown in Figure 4 having a bead 60 along one edge with its outer face substantially perpendicular to the top and bottom faces of the strip and having a complete grain surface. This welt strip is attached to the 65 shoe as shown in Figure 5 overlying the outwardly turned margins of the upper and lining as at 15 and 16, with the inner edge of the bead resting against the outer face of the 70 upper inwardly of said out-turned margin, the welt, upper, lining and sole being secured together by a line of stitching 17 extending 75 through the welt outwardly of the bead.

In place of forming the core strip and covering layer integrally, they may be formed 80 separately as shown in Figure 6, where the core strip 20 is shown as severed entirely from the remainder of the base strip and the covering or surfacing layer 21 may be formed by cutting inwardly from one edge of the 85 base strip to a sufficient extent to permit the core strip to be inserted thereunder, or the cover strip may be severed entirely from the blank (as shown by dotted lines in Figure 6) and then replaced after the core strip 20 90 has been placed in position along and flush with one edge thereof. Or of course, if desired, the cover strip might be formed of an entirely separate layer of material. In what- 95 ever manner formed, however, the cover strip is fixed to enclose the core strip 20 and to overlie this core strip and the adjacent flat face of the welt on the outer side of the bead.

If desired also, the welt may be orna- 100 mented in any manner desired, as shown in Figure 8, such ornamentation comprising stripes 25 and 26 of contrasting color ar- ranged crosswise of the bead portion only of the welt, the outer flat portion remaining unornamented.

Having thus described certain embodiments of this invention, it should be evident to those skilled in the art that various changes

and modifications might be made therein without departing from its spirit and scope as defined by the appended claims.

I claim:

- 5 1. A welt comprising a base strip having a bead projecting from one face of and flush with one edge of said base strip.
2. A welt comprising a strip having a longitudinally extending bead member having side portions extending substantially perpendicularly to the adjacent face of the strip, and a surfacing therefor split from the strip.
- 15 3. A welt comprising a flat strip having a longitudinally extending bead having side portions extending substantially perpendicularly to the adjacent face of the strip, one of said side portions lying in substantial alignment with an edge of the strip.
- 20 4. A welt having a longitudinally extending bead on one face thereof formed of a core strip of substantially square cross section overlaid with a surface layer attached by one end to the strip.
- 25 5. A welt comprising a base strip having a bead on one face formed of a core strip, one

side of said core strip being flush with one edge of the base strip and the other side of said core strip being overlaid with a surface layer.

20 6. A leather welt comprising a base strip having a bead on one face formed of a leather core strip having a grain side and a flesh side, said grain side being flush with one edge of the base strip and said flesh side being overlaid with a layer of grain leather.

35 7. The method of forming a welt which comprises inserting a core strip having side faces extending substantially perpendicularly to its base beneath a layer cut from the upper face of a strip of material, and fixing said core base on the cut face of said strip and said layer overlying said core.

40 8. The method of forming a welt which comprises fixing the base of a core having sides extending perpendicularly to said base to one face of a strip, and overlying said core with a surfacing layer split from the strip.

45 In testimony whereof I have affixed my signature.

HARRY LYON.
